UNITED STATES PATENT OFFICE.

HOWARD WHITE, OF BURMONT, PENNSYLVANIA.

DESIGN FOR A VENTILATOR-BAR.

SPECIFICATION forming part of Design No. 35,006, dated August 27, 1901.

Application filed April 23, 1901. Serial No. 57,143. Term of patent 14 years.

To all whom it may concern:

Be it known that I, HOWARD WHITE, a citizen of the United States of America, residing at Burmont, in the county of Delaware and 5 State of Pennsylvania, have invented and produced a new and original Design for Ventilator-Bars, of which the following is a specification, reference being had to the accompanying drawings, forming part thereof.

10 Figure 1 is a perspective view of a ventilator-bar, showing my new design. Fig. 2 is an end view thereof.

15 My invention relates to the form or configuration of a ventilator-bar; and it consists of the design shown in said drawings, in which the leading feature is an oblong bar having on the front face thereof a longitudinally-extending recess with oppositely-inclined surfaces *a a*. The back *b* of the bar is inclined,

20 and its upper and lower edges *c d*, respectively, are of less width than the height of the bar. The recess extends from end to end of the bar, the upper inclined surface of such recess being a flat surface disposed at right angles, or substantially so, to the lower edge 25 of the bar, which edge is also a flat surface. The bar is of uniform cross-section throughout its length.

I claim—

20 The design for a ventilator-bar, substantially as herein shown and described.

In testimony whereof I have hereunto affixed my signature in the presence of two subscribing witnesses.

HOWARD WHITE.

Witnesses:

ANDREW V. GROUPE,
JOHN R. NOLAN.
